UNITED STATES PATENT OFFICE.

WILLIAM H. SAUVAGE, OF NEW YORK, N. Y., ASSIGNOR, BY MESNE ASSIGNMENTS,
TO GOULD COUPLER COMPANY, OF NEW YORK, N. Y.

SLACK ADJUSTER.

Application filed July 11, 1923. Serial No. 650,916.

To all whom it may concern:

Be it known that I, WILLIAM H. SAUVAGE, citizen of the United States, residing at New York, in the county of New York and State 5 of New York, have invented certain new and useful Improvements in Slack Adjusters, of which the following is a specification.

This invention relates to improvements in slack adjusters, and more particularly to 10 that type of slack adjuster illustrated and described in my co-pending application, Serial No. 556,201, filed April 24, 1922.

One of the objects of the present invention is to provide a simple and practical 15 slack adjuster of the above general character, which will be reliable and efficient in operation and automatically regulate the tension or compression members connected either with the foundation rigging beneath 20 the car floor or the truck brake rigging. For convenience, the invention will be hereinafter described with reference to the latter application, although it is to be understood that without material modification various 25 features thereof may be adapted without material change to the foundation brake rigging.

A further object is to provide a durable 30 and strong automatic slack adjuster which will insure predetermined and uniform piston travel or hand brake operation at all times.

A further object is to provide a practical 35 and efficient device which may be easily and quickly applied to standard brake rigging equipment without material alteration of the remaining parts.

A further object is to provide an inexpensive mechanism having relatively few 40 parts, which may be inexpensively manufactured and assembled.

Other objects will be in part obvious and in part hereinafter pointed out in connection with the following analysis of this invention, when taken in connection with the 45 accompanying sheet of drawing illustrating one of various possible embodiments of the invention, and in the several views of which corresponding parts are denoted by similar 50 reference characters.

In these drawings—

Figure 1 is an elevational view showing a 55 four-wheel truck and frame in outline with the live and dead levers and associated parts of the adjuster shown more in detail; and

Figure 2 is a detailed view showing one end of the slack adjuster mechanism.

Referring now to the drawings in detail, 60 10 denotes a truck frame with which are associated two wheels 11 the peripheries of which are adapted to be engaged by the brake shoes 12 carried by brake shoe beams 13. These beams are actuated by live and dead levers 14 and 15, respectively, the lever 14 being actuated by a pull-rod shown diagrammatically at 16, while the upper end of the dead lever 15 is adjustably supported by a fulcrum 17 secured to the truck frame. The lower ends of the live and dead levers are 65 connected to opposite ends of a connecting rod 18 preferably formed of two parallel flat steel bars pivotally connected at 20 to the lower end of the dead lever and at 21 to the lower end of the live lever.

The pivot 21 passes through an elongated 70 slot 22 in the connecting rod 18 and has directly associated therewith a gravity-actuated pawl 23 coacting with a ratchet or rack 24 on the upper surface of the connecting rod 18. Midway between the lower end of the live lever 14 and its connection 25 with the brake beam strut 13 is a second gravity-actuated pawl 26 pivoted at 27 and adapted 75 to co-act with a second rack 28 on the upper surface of the connecting rod 18.

It will be noted that the racks 24 and 28 are separated by a blank space 30 and also 80 that these racks are of different size. In practice, it is preferred to make the rack 24 about five and one-quarter inches long, each 90 tooth approximately three-fourths of an inch in length and 3-eighths of an inch in depth. The ratchet or rack 28 is of substantially the same length, that is, five and one-fourth inches, but the teeth are only one-half inch long and about five-sixteenths of an inch in depth. The reasons for this construction will probably be clearer from the 95 following statement of operation.

In operation, the upper end of the live lever 14 is moved relatively towards the right on application of the brakes. If any excess travel takes place, due to wear of the 100 brake shoes, the peripheries of the wheels, or other parts, then the pawl 26 moves over one tooth on the rack 28 or one-half inch, and, as the brakes are released and the parts 105 return to normal position, as shown in Figure 1, this slack is taken up and the lower end of the live lever, indicated by the pivot 110

pin 21, is moved relatively towards the right along the slot 22. If the total excess travel at that time is greater than one-half inch, as provided for by the rack 28, then the 5 second pawl 23 will engage the next adjacent tooth to the right in the rack 24, thereby completely taking up and holding all of the excess travel. As the larger part of the strain comes upon this second pawl 23 during application, it is desirable to have the rack 24 heavier and the teeth made substantially the same in order to properly take up this excess strain. The parts remain in this 10 relative position during the application and release of the brakes until such wear occurs as will again cause a repetition of the above operation; that is, the pawl 26 will slide over one tooth of the rack 28 and, as soon as the wear increases beyond this distance, 15 then the pawl 23 will slide over the next adjacent tooth of the rack 24.

By having these racks of different sizes, it will be noted that the excess travel is 20 really taken up when the wear of the parts exceeds an amount corresponding to the difference between the three-fourths inch teeth and the one-half inch teeth. In other words, approximately every quarter inch of 25 excess travel at the slack adjuster will cause an operation of one pawl or the other, thereby permanently to take up and hold this excess travel.

The blank space 30 between the two rack 30 sections is utilized especially when the slack adjuster has moved the full distance towards the right and the brake shoes are not at once replaced. Thus, assuming that the pawl 26 has moved to the right hand end of the rack 28 and pawl 23 likewise, and further wear 35 takes place, then the pawl 26 will merely ride up on the upper surface of the blank space 30, and, on release, will drop back into the first adjacent tooth and the second pawl 23 remains stationary in the last tooth or 40 notch. The end of slot 22 also prevents any further movement of the pawl 23 towards 45 the right.

The present device is, therefore, more reliable and efficient than previous devices. 50 The mechanism is of simple, inexpensive and durable construction well adapted to accomplish among others all of the objects and advantages hereinafter set forth.

Without further analysis, the foregoing 55 will so fully reveal the gist of this invention that others can, by applying current knowledge, readily adapt it for various applications without omitting certain features that, from the standpoint of the prior art, fairly 60 constitute essential characteristics of the generic or specific aspects of this invention, and, therefore, such adaptations should and are intended to be comprehended within the meaning and range of equivalency of the 65 following claims.

I claim:

1. In an automatic slack adjuster, in combination, a live lever, a connecting rod pivotally connected therewith and having an elongated slot whereby relative change in the pivotal connection with respect to the connecting rod may take place, said connecting rod having a plurality of racks associated with its upper surface and pawls carried by said live lever for engaging said racks progressively. 70

2. In an automatic slack adjuster, in combination, a live lever, a connecting rod pivotally connected therewith and having an elongated slot whereby relative change in the pivotal connection may take place, said connecting rod having a plurality of racks associated with its upper surface and pawls carried by said live lever engaging said racks progressively, said racks being of different size. 80

3. In an automatic slack adjuster, in combination, a live lever, a connecting rod pivotally connected therewith and having an elongated slot whereby relative change in the pivotal connection may take place, said connecting rod having a plurality of racks associated with its upper surface and pawls carried by said live lever engaging said racks progressively, said racks being separated by a blank space, thereby to limit the progressive movement of the live lever 90 with respect to the rod. 95

4. In an automatic slack adjuster, in combination, a live lever, a connecting rod pivotally connected therewith and having an elongated slot whereby relative change in the pivotal connection may take place, said connecting rod having a plurality of racks associated with its upper surface and pawls carried by said live lever engaging said racks progressively, said racks being of different size and separated by a blank space, thereby blanking the pawl from further engagement with teeth to prevent full release of the live lever. 100

5. In an automatic slack adjuster, in combination, a live lever, a dead lever, a connecting rod pivotally connected with the lower ends of said levers and provided with an elongated slot at one pivotal connection whereby relative movement may take place, and pawls carried by said live lever one above the other, one being substantially midway between the pivotal point of the live lever and its pivotal connection with the connecting rod, and racks of different size on the upper surface of said connecting rod adapted to be engaged by said pawls one after the other to permanently take up and hold the excess movement due to wear of the parts. 110

6. In an automatic slack adjuster, in combination, a live lever and dead lever, a connecting rod pivotally connected with the 115

lower ends of said levers, one of said connections including an elongated slot for permitting relative movement between the live lever and its connection with the connecting rod, a plurality of racks spaced apart upon the upper surface of said connecting rod, and a plurality of pawls associated with the live lever and engaging said racks.

7. In an automatic slack adjuster, in combination, a live and dead lever, a connecting rod pivotally connected with the lower ends of said levers, one end of said connection including an elongated slot for permitting relative movement between the live lever and its connection with the connecting rod, a plurality of racks spaced apart upon one surface of said connecting rod, and a plurality of pawls associated with the live lever and engaging said racks, the size of the teeth of one rack differing from the size of the teeth of the other rack whereby the holding pawls progressively take up and hold excess wear of the parts.

8. In an automatic slack adjuster, in combination, live and dead levers, a connecting rod pivotally connected with the lower ends of said levers, one end of said connection including an elongated slot for permitting relative movement between the live lever and its connection with the connecting rod, a plurality of racks spaced apart upon one sur-

face of said push rod, and a plurality of pawls associated with the live lever and engaging said racks, the size of the teeth of one rack differing from the size of the teeth of another rack whereby the holding pawls progressively take up and hold excess wear of the parts, said pawls being gravity actuated.

9. In an automatic slack adjuster, in combination, a live lever, a connecting rod having a slotted pivotal connection therewith, racks on one surface of said connecting rod, and pawls carried by the live lever engaging said racks, said racks being of different size and spaced apart one from the other, thereby to limit the relative movement taking place between the live lever and the connecting rod.

10. In an automatic slack adjuster, in combination, a live lever, a truck brake beam pivotally connected near the central part thereof, a connecting rod connected with the lower end of said live lever and having a slotted connection therewith to permit relative movement, said connecting rod having a plurality of racks associated with its upper surface and pawls carried by said live lever for engaging said racks progressively.

In witness whereof I have signed my name this 24th day of May, 1923.

WILLIAM H. SAUVAGE.
